UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,163,331.

Specification of Letters Patent.

Patented Dec. 7, 1915.

Application filed November 21, 1914. Serial No. 873,259.

To all whom it may concern:

Be it known that I, FRANZ A. FULLER, a citizen of the United States, residing at Newark, in the county of Essex and State of New Jersey, have invented certain new and useful Improvements in Bag-Fasteners, of which the following is a specification, reference being had therein to the accompanying drawings, which form a part thereof.

10 My invention relates to bag fasteners and more particularly to a type thereof applicable to bag frames having pivotally connected frame members and embodying therein a lift latch adapted to lock said frame members when closed.

15 Bag frames of the character above referred to are made of members formed of channeled metal stock, the edges of the bag body being adapted to be inserted and secured within the channel of the frame members. It is also a general custom to cover the frame members, the edges of the covering material being folded within said channel.

20 A bag fastener made in accordance with my invention is so constructed that its attachment to the frame members may be accomplished without obstructing the channel of said members to an extent to interfere, in any substantial degree, with the operations of covering the frames or of mounting the bag body therein.

25 The spring acting upon the lift member or knob is so constructed and combined with relation to said member or knob as to occupy a position in the frame which will not interfere with the attachment of the bag body to the frame; and to coöperate with said frame member in a manner to cause the assembling of the spring and the lift member or knob in relation to the frame member to develop a torsional stress upon the spring which will serve to maintain the lift member or knob normally in the operative 30 position, while at the same time allowing a sufficient side sway of the spring to compensate for the slight lateral component of movement of the spring lug resulting from the actuation of the lift member or knob.

35 A bag fastener made in accordance with my invention is so simple in its construction as to not only be capable of being inexpensively produced, but to permit the assembly of the latch mechanism in relation to the 40 frame members, in a manner to preserve the

artistic lines of the frame. It is a common practice to provide frames of this character with decorative metal sections adjacent the latch mechanism, both as to the lift latch and the nose or catch coöoperating therewith. 45 My invention contemplates a bag frame structure wherein such decorative metal sections may be applied to the frame after it has been covered in its entirety, thus avoiding the necessity for cutting and fitting the 50 covering strip to and about the decorative plates. This construction has the advantage that in addition to simplifying the covering operation of the frame, it secures a neat finish to the covered frame about the decorative metal. It also eliminates the possibility 55 of the separation of the covering from the frame adjacent the latch which portion of the frame is subjected to greater wear than any other part thereof. In applying the 60 decorative metal parts to the frame, I utilize as a securing means, the different parts of the latch mechanism, and thus not only simplify and cheapen the bag structure, but secure a reinforced wear surface adjacent this 65 mechanism.

70 The invention consists primarily in a bag fastener embodying therein a frame consisting of hinged frame members, one of which has an opening in the top thereof, a 75 lift latch member or knob provided with a lug adapted to project through said opening and within said frame, a spring, one portion of which is adapted to be operatively connected with said lug and another portion of which is projected substantially radially of said lug and adapted to engage a side wall of said frame whereby the positioning of said spring in relation to said lug and frame member will subject it to a 80 torsional stress adapted to normally seat said lift member, and a nose or catch carried by the other frame member and adapted to be operatively engaged by said lift member; and in such other novel features of construction and combination of parts as are 85 hereinafter set forth and described and more particularly pointed out in the claims 90 hereto appended.

95 Referring to the drawings: Figure 1 is a 100 perspective view of a bag frame having applied thereto a fastener embodying my invention, a portion of one of the frame members being broken away; Fig. 2 is a vertical section of a portion of a bag frame adjacent 105

the fastener; Fig. 3 is a section on the line 3—3 of Fig. 2; Fig. 4 is a section of the frame member carrying the nose or catch; Fig. 5 is a detailed view of the spring; Fig. 6 is a transverse section of a bag frame showing a modification of the invention as to the manner of securing the spring in its position with relation to the frame member; and Fig. 7 is a similar view of a still 10 further modification showing one manner of securing the spring when a rectangular frame is employed.

Like letters refer to like parts throughout the several views.

15 In the embodiment of my invention shown in the drawings, the frame members are shown at $a-b$, the main body of said members being provided with hinge members $a'-a^2$, $b'-b^2$ respectively. Said hinged 20 members are pivotally connected at $c-c'$. In the forms of the invention shown, the frame members $a-b$ are composed of channeled metal stock. The faces of said members presented toward each other when the 25 bag is closed are substantially parallel and the tops thereof are reduced by a graduated curve of the outer walls of said members, thus presenting a channel constricted toward the top thereof. One of said members, 30 as a , has through the top thereof, at any desired point, an opening d adapted to receive the spring lug upon the lift member or knob. The other frame member, as b , is provided with an outwardly presented nose 35 or catch e of the usual and well-known construction.

The lift member or knob f , carried by the frame member a is provided with a pendant rim or keeper f' adapted to operatively engage the nose or catch e and also with a 40 spring lug g . An angular opening extends longitudinally through said lug, or other means are provided upon said lug whereby it may be operatively connected with its 45 controlling spring. This lug is adapted to project through the opening d in the frame member a , and within the channel of said frame to a sufficient extent to expose the opening therein within said channel closely 50 adjacent the top thereof. The keeper rim f' is adapted to overhang the frame member b and to pass over and operatively engage the nose or catch e .

The controlling spring comprises a 55 straight section h preferably of round spring wire having a portion thereof i bent at an angle to said straight section, so as to be projected toward the inner wall of the frame member a when it is assembled in the 60 latch. To simplify the structure of this spring, I preferably merely turn the end thereof as shown. The other end of said spring is adapted to be operatively connected with the lug g of the lift member, 65 preferably by being flattened as at j so as

to have a sliding fit with the angular opening in the said lug g . I also preferably provide said spring with a stop shoulder k adapted to define the movement of said spring when applying it to said lug, and also for accurately positioning the projection i in relation to its coöperating shoulder upon the frame a . This stop shoulder is preferably formed by a short bend in the said spring. 75

To guard against displacement of the controlling spring, I form a slight depression as l in the top of the frame member a and form in the spring adjacent the projections i thereof a small notch m forming an extension adapted to enter said depression. Below said recess l , I form a seat n for the end of the projection i . This seat may be formed in any desired manner as by pressing in the lower edge of the frame as shown 80 in the preferred form of the invention, or by pressing the metal outwardly as shown at n' in the modification shown in Fig. 6. To insure against the displacement of the end of the said projection with relation 85 to the seat n or n' I preferably flatten said projection and bring the end thereof to an edge adapted to rest firmly upon said seat. By this means, I am enabled to reduce the width of the seat, and at the same time 90 cause the projection to take a sufficiently firm bite thereon. When the seat is formed by pressing the metal inwardly, as in the preferred form of the invention, I have found there is a slight tendency of the projection i to be forced from this seat when the edges of the bag are being connected to the frame member and to obviate this condition, I preferably arch said projection 95 slightly as shown in Fig. 3 of the drawings. 100

When the channel of the frame member a is constricted at the top thereof, as shown in Figs. 1 to 6 of the drawings, the spring section h will have insufficient side play or sway to permit the movement of the lift member or knob f to displace the projection i . When, however, the fastener is applied to a frame member angular in cross section, this side play or sway of the spring would not be limited by the frame member, 110 and to guard against a tendency toward the unseating of the projection by reason thereof, a confining block n^2 may be soldered or otherwise secured within the top of the frame member adjacent the said projection 115 as shown in Fig. 7 of the drawings, or a depression similar to n in Fig. 3 may be used. Each of the frame sections a and b is covered with any desired material, indicated at o . This covering consists of a continuous strip of material extending from adjacent one hinge c to adjacent the other hinge c' , the edges thereof being lapped over and within the sides of the channels of each frame member $a-b$. After the ap- 120

lication of this covering strip, decorative metal plates p — q are mounted upon each frame member a — b exteriorly of said covering material and adjacent the nose or catch e and the lift member or knob f respectively, the edges of said plates being formed to the said frame members. The plate p is held in position by the lift member of knob f and serves as a reinforcement for the frame adjacent said knob, and as a washer against which said knob bears. The plate q is pierced to receive the stem of the nose or catch e and is attached to the frame member b solely by means of said nose or catch.

In assembling the device, the lug g is projected through the opening d and through the opening in the plate p when this plate is used the controlling spring is then operatively connected with said lug by merely inserting the flattened end j thereof in the angular spring socket in said lug. In connecting said spring to said lug and in forcing the spring to place in the frame member a , the projection i will be so positioned as to engage the inside wall of the said frame member, and the subsequent movement of the spring toward the top of the channel will have the effect of placing the sections h — j under a torsional stress as well as under a direct tension toward the outer wall, the result of which will be the exertion of a normal tendency of the spring to tilt the lift member of knob f toward the frame member b . As the controlling spring comes to seat, the flattened end of the projection i will enter the recess above and seat upon the seat n the notch m adjacent said projection entering the recess l in the top of the frame. The engagement of the stop shoulder k with the edge of socket of the lug g , will accurately position the projection i with relation to the seat n .

I prefer to form the seat for the spring projection i in the manner shown in Figs. 1 to 5 because the area of this seat is so small that the metal of the side of the frame may be readily formed inwardly and there will be no resultant protuberance appearing upon the outer face of the wall of the channel. This protuberance would necessarily result in the form of the invention shown in Fig. 6, and would require that the outer wall of the frame be ground off to make it parallel throughout with the inner wall of the frame member b . In raising the lift member or knob the lug g will have both a rotary and a lateral movement, which will serve to increase the torsional, as well as the direct tension, of the spring. The length of the section h , however, is such as to accommodate the spring to both of these actions without making the tension of the spring too great.

It is not my intention to limit the invention to the precise details of construction

shown in the drawings, it being apparent that such may be varied without departing from the spirit and scope of the invention.

Having described the invention what I claim as new and desire to have protected by Letters Patent is:—

1. A bag fastener embodying therein a frame consisting of hinged frame members, one of which has an opening in the top thereof, a lift member or knob provided with a lug adapted to project through said opening and within said frame member, a spring, one portion of which is adapted to be operatively connected with said lug, and another portion of which is projected substantially radially of the axis of said lug and adapted to engage the side wall of said frame, whereby the positioning of said spring in relation to said lug and said frame member will subject it to a torsional and a lateral stress adapted to normally seat said lift member, and a nose or catch carried by the other frame member and adapted to be operatively engaged by said lift member.

2. A bag fastener embodying therein a frame consisting of hinged frame members one of which has an opening in the top thereof, a spring seat formed on the inner side wall of said frame adjacent said opening, a lift member or knob, a lug having an angular socket therein carried by said member or knob and adapted to project through said opening and within said frame member, a spring having one end thereof flattened so as to have a sliding fit with said socket in said lug and the other end of which is turned at an angle and adapted to engage the side wall of said frame and rest upon said spring seat whereby the positioning of said spring in relation to said lug and said frame member will subject it to a torsional and a lateral stress adapted to normally seat said lift member, and a nose or catch carried by the other frame member and adapted to be operatively engaged by said lift member.

3. A bag fastener embodying therein a frame consisting of hinged frame members one of which has an opening in the top thereof, a spring seat formed on the inner wall of said frame member adjacent said opening, said frame member having a depression in the top above said spring seat, a lift member or knob, a lug having an angular socket therein carried by said member or knob and adapted to project through said opening and within said frame member, a spring having one end thereof flattened so as to have a sliding fit with said socket in said lug and the other end of which is turned at an angle and adapted to engage the side wall of said frame and rest upon said spring seat whereby the positioning of said spring in relation to said lug and said frame member will subject it to a torsional and a lateral stress adapted to normally seat said lift member,

said spring adjacent said turned end having a notch formed therein adapted to seat in the said depression in the top of said frame member, and a nose or catch carried by the 5 other frame member and adapted to be operatively engaged by said lift member.

4. A bag fastener embodying therein a frame consisting of hinged members, one of which has an opening in the top thereof, the 10 inner wall of said frame being formed inwardly adjacent the edge thereof to produce a spring seat adjacent said opening, a lift latch member or knob, a lug having an angular spring socket therein, carried by said 15 lift member or knob and adapted to project through said opening and within said frame, a spring having the ends thereof flattened, one end of said spring having a sliding fit with said spring socket in said lug, and the

other end thereof being projected at an angle 20 so as to engage the side wall of the frame member and rest upon said seat, said bent end being arched longitudinally and away from the wall of said frame member, whereby the positioning of said spring in relation 25 to said lug and said frame member will subject it to a torsional and a lateral stress adapted to normally seat said lift member, and a nose or catch carried by the other 30 frame member and adapted to be operatively engaged by said lift member.

In witness whereof I hereunto affix my signature in the presence of two subscribing witnesses, this 14th day of November 1914.

FRANZ A. FULLER.
